R. C. DANLY

AUTOMATIC WORK STOP

Filed March 5, 1923

Inventor.
Robert C. Danly,
by Robert Burns.
Atty

UNITED STATES PATENT OFFICE.

ROBERT C. DANLY, OF CHICAGO, ILLINOIS, ASSIGNOR TO DANLY MACHINE SPECIALTIES, INC., OF CHICAGO, ILLINOIS, A CORPORATION OF ILLINOIS.

AUTOMATIC WORK STOP.

Application filed March 5, 1923. Serial No. 622,817.

To all whom it may concern:

Be it known that I, ROBERT C. DANLY, a citizen of the United States of America, and a resident of Chicago, in the county 5 of Cook and State of Illinois, have invented certain new and useful Improvements in Automatic Work Stops, of which the following is a specification.

This invention relates to automatic stop mechanisms for punch presses and more especially for standard punch and die sets used in connection with such presses, and adapted to stop and position the stock or plate material operated on after each successive operation of the punching mechanism, and this improvement has for its objects:—

To provide a formation and combination of parts and elements in which a stop pin 20 is moved from stop engagement with an opening in the stock operated on in the active stroke of the punch mechanism, and automatically shifted into a position of rest upon the top of said stock ready to drop 25 into stop engagement with a succeeding opening in said stock.

To provide a formation and association of parts of an automatic stop mechanism adapted for ready and accurate application 30 to the stripper plate of a punching mechanism, all as will hereinafter more fully appear.

In the accompanying drawings:—

Fig. 1, is a detail longitudinal section of 35 the lower portion of a blanking punch and die set having the present improvement applied.

Fig. 2, is a plan view of the stripper plate with the improvement in place.

Fig. 3, is a detail sectional elevation illustrating the position of the stop mechanism parts with the stop pin in active stop engagement in an opening in the stock operated on to properly position the same.

Fig. 4, is a companion view showing said stop pin above and resting upon the stock, ready to drop into a succeeding opening in said stock in a feed of the same.

Fig. 5, is another companion view showing said stop pin dropped down into the succeeding opening in the stock, and previous to the movement of the pin to the stop position shown in Fig. 3.

Fig. 6, is a perspective view of the parts 55 of the stop mechanism in a detached position.

Fig. 7, is a detail longitudinal section illustrating the stop mechanism applied to the movable stripper plate of a punching 60 and drawing type of die sets.

Like reference numerals indicate like parts in the several views.

In the drawings: 1, designates the bed plate or holder for the die 2 of a punch 65 and die set, adapted to be clamped in place on the bed of a punch press, and provided with the usual leader pins 3 for guiding engagement with an associated punch carrying head 4, a portion of which is shown 70 in Fig. 1, with said punch carrying head having attachment to and movement with the punch press plunger as usual.

5, designates the stripper plate, which in a blanking punch and die set as shown in 75 Figs. 1, 2 and 3 is formed on its underside with the usual guide throat or channel for the stock operated on. In such type, the stripper plate 5 is fixedly secured to the top of the die 3 as shown. In the 80 punching and forming type of punch and die sets shown in Fig. 7, the stripper plate 5' has limited vertical movement with relation to the central upstanding portion of the die 2, and has limited upward movement under the stress of a series of springs 85 7, while its positive downward movement is effected by the movable punch carrying head of the set. The construction so far described has been in general use for an 90 extended period in modern manufacturing establishments in this country.

8, designates a circular shouldered head adapted to fit and be secured in a corresponding shape orifice in the stripper plate 95 5, and in the present improvement the head 8 is formed at its upper end with a central cross slot providing a pair of orificed ears 9 for the pivotal mounting of the hereinafter described rocker bar, which is attained by a pivot 10 passing through the ears 9 and through said rocker bar.

11, designates the rocker bar above referred to, pivoted at its mid-length in the head 8 by a pivot pin 9 aforesaid, and extending longitudinally of the stripper plate 5. One arm 12 of said rocker bar is arranged in a plane above the stripper plate

with its free end in the path of an adjustable contact stem or bolt 13, which in the construction shown in Fig. 1, is carried by the punch carrying head 4 of the mechanism, while in the construction shown in Fig. 7, the stem or bolt 13' is carried by the die 2. In either construction the function attained is the rocking of the rocker bar 11, for the purpose hereinafter described.

14, designates a spring arranged beneath the arm 12 of the rocker bar 11, with a resilient tendency to move said arm in an upward and opposite direction to that effected by the stem or bolt 13 aforesaid.

The other arm 15 of the rocker bar 11, has movement in a surface recess in the stripper plate 5, and has operative connection with the stop pin for the stock, as follows:—

16, designates an orifice extending vertically down through the stripper plate 5 and arranged in spaced longitudinal relation to the orifice in which the aforesaid circular head 8 is arranged, and has connection with said orifice by a surface recess in the stripper plate 5, in which recess the arm 15 aforesaid has movement.

17, designates a cylindrical stop pin arranged in the orifice 16 aforesaid, and 30 adapted to have limited tilting movement as well as a vertical adjustment therein. In its working position, the lower end of the stop pin 17 rests upon the top surface of the die 2, and is located at a point in the guide 35 throat or channel of the stripper plate 5 aforesaid, to engage and stop the stock operated on at the proper point for a punching operation, and with a view to an effective automatic operation, the stop pin 17 is 40 operatively connected to the arm 15 of the rocker bar 11 by intermediate means as follows:—

18, designates a longitudinal guide bore in the rock bar arm 15, adapted to receive 45 an inner spring member 19 and an outer sliding plug 20, the outer end of which plug is of a rounded formation adapted for operative engagement in a lateral recess 21, in the upper end of the stop pin 17 as shown.

50 With the described construction, the spring 19 and plug 20 tends to hold the stop pin 17 in a vertical position against the forward side of the vertical orifice 16 as shown in Figs. 1, 4 and 5, and so that in the operation of the stop mechanism, as the stock operated on nears the proper punching position, either an advancing end or the like advancing end of a punched opening in the stock abuts against and moves or tilts the 55 stop pin 17 to the oblique position shown in Fig. 3, in which position the parts remain during a punching operation. With a descent of the punch carrying head 4, the contact stem or bolt 13, operatively engages the 60 arm 12 of the rocker arm 11 to impart a

rocking motion thereto, and which in turn acts to lift the stop pin 17 out of engagement with the stock after which the spring 19 acts to return the stop pin 17 to its normal vertical position with its lower end resting on the top surface of the stock as illustrated in Fig. 4, and ready to drop into the newly made punched opening in the stock on a succeeding feed of said stock as illustrated in Fig. 5, and prior to the full feed 75 of said stock into the first described position shown in Fig. 3.

Having thus fully described my invention what I claim as new and desire to secure by Letters Patent, is:—

1. In an automatic work stop for punch and die mechanisms, the combination of a rocker bar mounted on the stripper plate of the mechanism, a stop pin arranged in a vertical orifice in said stripper plate and 85 adapted to have a limited tilting movement as well as vertical adjustment in said orifice, one arm of the rocker bar having resilient operative connection with said stop pin, and an adjustable abutment stem adapted for 90 operative engagement with other arm of the rocker bar in an active stroke of the punch and die mechanism.

2. In an automatic work stop for punch and die mechanisms, the combination of a 95 rocker bar mounted on the stripper plate of the mechanism, a stop pin arranged in a vertical orifice in said stripper plate and adapted to have a limited tilting movement as well as vertical adjustment in said orifice, one arm of the rocker bar having a longitudinal recess, an inner spring and a movable outer plug arranged in said recess with the outer end of the plug having operative engagement in a lateral recess in the stop pin aforesaid, and an adjustable abutment stem adapted for operative engagement with the other arm of the rocker bar in an active stroke of the punch and die mechanism.

3. In an automatic work stop for punch 110 and die mechanisms, the combination of a shouldered head adapted for attachment in an orifice in the stripper plate of the mechanism and formed with a slot in its upper end, a rocker bar pivoted at its mid-length 115 in said slot, a stop pin arranged in a vertical orifice in said stripper plate and adapted to have a limited tilting movement as well as a vertical adjustment in said orifice, one arm of the rocker bar having resilient operative 120 connection with said stop pin, and an adjustable abutment stem adapted for operative engagement with the other arm of the rocker bar in an active stroke of the punch and die mechanism.

4. In an automatic work stop for punch and die mechanisms, the combination of a shouldered head adapted for attachment in an orifice in the stripper plate of the mechanism and formed with a slot in its upper end, 130

a rocker bar pivoted at its mid-length in said slot, a stop pin arranged in a vertical orifice in said stripper plate and adapted to have a limited tilting movement as well as 5 a vertical adjustment in said orifice, one arm of the rocker bar having a longitudinal recess, an inner spring and a movable outer plug arranged in said recess with the outer end of the plug having operative engage- ment in a lateral recess in the stop pin afore- 10 said, and an adjustable abutment stem adapted for operative engagement with the other arm of the rocker bar in an active stroke of the punch and die mechanism.

Signed at Chicago, Illinois, this 2nd day 15 of March, 1923.

ROBERT C. DANLY.
